UNITED STATES PATENT OFFICE.

FRANK ARTHUR GOODHUE, OF WINCHESTER, MASSACHUSETTS.

SIGNALING DEVICE.

Application filed February 2, 1920. Serial No. 355,558.

To all whom it may concern:

Be it known that I, FRANK A. GOODHUE, a citizen of the United States, and a resident of Winchester, in the county of Middlesex 5 and State of Massachusetts, have invented certain new and useful Improvements in Signaling Devices, of which the following is a specification.

This invention relates to automobile signals and has for its object the provision of novel means whereby the signal hand may be promptly returned to its inoperative position within a casing upon being released, and further the invention has for an object 15 the provision of novel means whereby the spring which returns the signal hand to its inoperative position is at all times enclosed and thereby protected from the elements.

A further object of the invention is to 20 provide an electric light in connection with the signal which is controlled by the movement of the signaling mechanism into operative and inoperative position.

In the drawings:

25 Figure 1 is a side view illustrating the improved signal applied to the fender of a motor vehicle, the view also illustrating the operating means for the signal.

Figure 2 is a side elevation of the signal 30 detached,

Figure 3 is a vertical sectional view through the signal, the view illustrating the arm in an elevated position.

The present embodiment of the invention 35 is shown in connection with a motor vehicle 1 of usual construction and the signaling mechanism is arranged on the rear fender, at the left in the present instance. This mechanism comprises a casing 2, substantially rectangular in cross section and relatively thin in one dimension and having one side open, as shown.

40 Within the casing there is mounted a semaphore arm 3 which, in the present instance, is shaped to simulate a pointing hand, and the said arm is pivoted in the casing as indicated at 4, near the top thereof, so that it may swing into or out of the casing to be completely hidden or to be partially exposed.

45 A spring 5 is connected with the semaphore arm and with the casing, and acts normally to swing the arm into the casing, the said spring being a resilient wire which 50 is wrapped about the signal arm and the pivotal connection, as shown, and has one

end hooked over the arm to normally draw the free end of the arm downward.

The other end of the spring is engaged with a stop 6 on the casing wall. The casing has an opening in its bottom and into this opening there is threaded a sleeve or nipple 7 through which the controlling mechanism for the signal arm passes. The said mechanism is a flexible member 8, as, 60 for instance, a cord, wire or the like, which is connected at one end to an opening 9' in the signal arm, on the opposite side of the pivotal connection from the representation of the fingers. This flexible member passes 70 downwardly through the nipple and through a tubular flexible casing or pipe 9 which is connected with the nipple at one end, and which is supported by an eye 10 on the frame near the other. 75

This nipple 7 engages an opening in the rear fender 11, as shown more particularly in Figure 1, and the pipe 9 is threaded on to the nipple below the fender, the casing 2 being above the fender. This pipe 9 passes 80 downwardly and inwardly beneath the adjacent side member of the frame of the vehicle and then upwardly to the level of the frame to the eye 10.

A coil spring 12 is connected with the 85 forward end of the flexible member 8, as shown in Figures 1 and 2, and two flexible members 13 and 14 are connected with the forward end of the spring. One of these flexible members, 13 in the present instance, 90 is connected with the clutch pedal, indicated at 15, while the other, namely, the flexible member 14, is connected with the brake pedal 16. The connection is by means of a collar 17 which encircles the pedal lever 95 and has an eye for connection with the flexible member. It will be evident that when the brake is applied or the clutch lever is operated to release the clutch, the initial movement of the pedal will swing the signal 100 arm into the position of Figures 2 and 3. As soon as the arm is in this position the further forward movement of the pedals is not interfered with, because the spring 12 will yield, permitting said forward movement 105 without interference from the pedal arm.

As illustrated in Figure 4, the coiled spring 5 having convolutions surrounding the pivot pin 4 has one terminal arm anchored to the casing as indicated at 6 and 110 the other terminal arm or portion is engaged with the signal hand 3 in advance of

the pivot pin 4. By reason of this construction the hand 3 is returned to its inoperative position immediately upon being released.

5 The upward swinging movement of the signal arm is limited by its engagement with the top of the casing 2, and when the arm engages the casing it cannot swing further and the spring 12 will immediately 10 expand, to permit the further forward movement of the pedal or clutch lever. The device is purely automatic, being controlled entirely by the movement of the clutch or pedal lever. No attention is required on the 15 part of the driver, nor is it necessary for him to take his hands from the control mechanism to operate the signal. He cannot operate either clutch or brake without operating the signal. In day light those 20 behind or in front can see the signal 3, that is, the pointing hand. In order that the signal may be visible at night, an electric light 18 is mounted on the signal arm, just below the representation of the index finger. 25 This bulb is held by a socket and lead wires 20 and 21 are connected with the socket. One of these wires, namely, the lead wire 20, is connected to a contact button 19 on the signal arm, as shown in Figure 3, and this

button is adapted to contact with the metallic case when the arm is in operative position, to close the circuit by grounding said circuit on the metallic case, the fender and the frame of the vehicle. The other lead wire 21 is connected to a source of electric 35 current.

I claim:

A signal comprising a vertically arranged casing having one vertical side open, a signal hand arranged in said casing and movable through the open side of the same to a horizontal position, a pivot pin extending transversely through said casing and supporting the signal hand for swinging movement, a spring having convolutions surrounding said pivot pin and having a terminal arm extended downwardly and anchored to the lower portion of the casing, said spring having a second terminal arm overhanging and engaging the upper edge 50 of the signal for promptly returning the signal hand to a vertical position upon being released, the rear portion of said signal hand being provided with an apertured ear, and an operating device connected to said 55 ear, said spring being entirely within the casing and protected thereby at all times.

FRANK ARTHUR GOODHUE.
